TOOL BRACE

Filed Nov. 29, 1924

INVENTOR.

R. D. HUTSON

BY
Watson E. Coleman
ATTORNEY.

UNITED STATES PATENT OFFICE.

ROY DOW HUTSON, OF ROSENDALE, MISSOURI.

TOOL BRACE.

Application filed November 29, 1924. Serial No. 752,908.

This invention relates to certain improvements in tool braces and has relation more particularly to a device of this general character especially designed and adapted 5 for use in connection with speed wrenches and it is an object of the invention to provide a device of this general character having novel and improved means whereby the tool holding chuck may be rotated in either 10 direction through the instrumentality of a ratchet mechanism or whereby the desired rotation of the tool holder may be created in substantially an automatic manner.

The invention consists in the details of 15 construction and in the combination and arrangement of the several parts of my improved tool brace whereby certain important advantages are attained and the device rendered simpler, less expensive and otherwise 20 more convenient and advantageous for use, as will be hereinafter more fully set forth.

The novel features of my invention will hereinafter be definitely claimed.

In order that my invention may be the 25 better understood, I will now proceed to describe the same with reference to the accompanying drawings, wherein:

Figure 1 is a view in elevation of the tool brace constructed in accordance with an 30 embodiment of my invention;

Figure 2 is a fragmentary view partly in section and partly in elevation of the device as herein disclosed;

Figure 3 is a sectional view taken sub- 35 stantially on the line 3—3 of Figure 2.

As disclosed in the accompanying drawings, 1 denotes an elongated tubular stock having its periphery serrated or otherwise roughened and in swivelled connection, as 40 at 2, and to the outer end portion of the stock 1 is the operating crank 3. The end portion of the stock 1 adjacent to the crank 3 extends within a suitable bearing 4 carried by the crank 3, that portion of the stock 1 within 45 the bearing 4 comprising a toothed wheel 5 with which are adapted to engage the pawls 6 arranged at either side of the crank 3 or more particularly the bearing 4 whereby the stock 1 may be intermittently rotated 50 in either direction and which is particularly desirable in connection with close work.

Freely insertible within the opposite end portion of the stock 1 and having movement lengthwise thereof is a shank 7 of desired 55 length and which is provided at its outer end with a chuck 8. The chuck 8 is of a

well-known type and is adapted to operatively hold a speed wrench bit or other tool bit of desired type.

The shank 7 is provided in its periphery 60 with the oppositely arranged spiral grooves 9 extending lengthwise thereof and in each of which is adapted to be selectively engaged either of the pawls 10 carried by the stock 1 and preferably housed therein as is illustrated in Figure 3.

By extending the shank 7 and engaging the desired pawl 10 in its associated groove 9 the resultant pressure or stress imposed upon the stock 1 and preferably through 70 the crank 3 will result in the desired rotation of the chuck 8 whereby a substantially automatic rotation of the chuck is accomplished. As herein disclosed the pawls 10 are pivotally supported within an internal chamber 11 suitably formed in the end portion 75 of the stock 1 opposed to the chuck 8, the pawls 10 being provided with the cam tail pieces or extensions 12 with which is adapted to coact the button 14 having sliding movement in a direction circumferentially of the stock 1 and as provided by the slot 16.

As illustrated in Figure 3, the button 14 is in a position to effect rotation of the chuck 8 in one direction and by moving said button 80 14 to the limit of its movement in the opposite direction, the chuck 8 will be caused to reversely rotate. With the chuck centrally positioned with respect to the pawls 10 the springs 15 coacting with the tail pieces or 85 extensions 12 of the pawls 10 will cause both of said pawls to engage within their grooves 9 whereby the shanks 7 and the chuck 8 are effectively held against rotation independently of the stock 1 and under which 90 conditions the crank 3 is adapted to be 95 employed.

It will also be understood that when the pawls 6 at each side of the crank 3 are engaged with the toothed wheel 5, the stock 100 1 will be caused to continuously rotate in either direction without coaction.

From the foregoing description it is thought to be obvious that a tool brace constructed in accordance with my invention 105 is particularly well adapted for use by reason of the convenience and facility with which it may be assembled and operated, and it will also be obvious that my invention is susceptible of some change and modification without departing from the principles 110 and spirit thereof and for this reason I do

not wish to be understood as limiting myself to the precise arrangement and formation of the several parts herein shown in carrying out my invention in practice except as 5 hereinafter claimed.

I claim:

A device of the class described comprising a tubular stock, a crank in swiveled connection therewith, the connected portion of 10 the crank being provided with a bearing, the connected portion of the stock extending within such bearing and constituting a toothed wheel, a pawl carried by the crank

at either side of the bearing and engageable with the toothed wheel, a shank freely insertible within the stock and having movement lengthwise thereof, a chuck carried by the outer end portion of the shank, and co-acting means carried by the shank and stock to rotate the shank and chuck independently 20 of the stock after the shank has been projected and stress imposed upon the stock.

In testimony whereof I hereunto affix my signature.

ROY DOW HUTSON.
